TYPEWRITING MACHINE

William F. Helmond, Clinton, Conn., assignor to
 Underwood Elliott Fisher Company, New York,
 N. Y., a corporation of Delaware

Application May 20, 1942, Serial No. 443,721

11 Claims. (Cl. 197—17)

This invention relates to typewriting machines embodying motor-drive means for moving or returning the carriage and/or operating typing or other instrumentalities.

The machine of the present invention embodies a cover which, according to the embodiment of the invention shown, normally shields the typing elements but which is displaceable to enable the operator to gain access to the interior of the machine for type-cleaning and other purposes. The cover, in its effective position, guards the operator against injury by the motor-driven parts within the machine, and, conversely, guards the motor-driven parts against injurious interference by the operator.

It is one of the objects of the invention to provide efficiently operative means which make it impossible to open such a cover while the machine is being motor driven.

It is a further object of the invention to provide reliably operative and simple means to make power operation of at least certain parts of the machine possible only in the closed position of said cover.

It is another object of the invention to provide means whereby energization of an electric motor is restricted to such times as the said cover is undisplaced.

Still another object of the invention is to attain the said above objects by simple and reliably operative means which prevent closure of a motor switch when the said cover is open and which further prevent opening of the cover when the switch is open.

The machine may be equipped with any suitable power carriage-return mechanism such, for example, as the one shown in the patent to Helmond No. 2,262,676, dated November 11, 1941.

Inasmuch as, according to the present invention, the motor or power drive of the machine is inoperative when the said cover is open, it follows that the carriage can only be power driven or power returned in the closed position of the cover. Stating it more specifically, regardless of what type of power-return mechanism may be employed, neither the operation of the carriage-return key nor movement of the carriage toward line-end position can cause a power return of the carriage as long as the cover is in a displaced position.

In many prior machines, as also in the one disclosed in the said patent to Helmond, a carriage return will ensue upon closure of the motor switch, if the carriage-return key or its equivalent has been operated prior thereto. This is

dangerous to the operator and otherwise undesirable, and, in view of this, it is a further object of the invention to provide a power-moving mechanism for the carriage that can only be called into operation in response to controlling operations effected while the motor circuit or switch is closed.

Still another object of the invention is to provide that power-movements of the carriage can only ensue in response to operations of the controlling mechanism effected after closure of the said cover.

Other objects and advantages of the invention will hereinafter appear.

15 In the drawings:

Figure 1 is a fractional perspective view of a typewriting machine embodying the invention and illustrating a normally locked displaceable cover unlocked due to the turning off of a power switch, the view also illustrating a carriage-return mechanism in a disabled condition.

Figure 2 is a fractional front view showing the power switch turned off and the cover opened; the power switch being incapable of 20 being turned on pending restoration of the cover to its closed position.

Figure 3 is a fractional front elevation showing the said cover restored and the power switch turned on,

25 Figure 4 shows a side elevation of the machine illustrating particularly a power typing mechanism and the aforesaid displaceable cover,

Figure 5 is a fractional front view of a portion of the carriage return mechanism, the mechanism being effectively conditioned.

30 Directing attention now to Figures 1 and 4, the typewriting machine may have an inner mechanism-supporting frame designated by the numeral 11. This inner frame may rise from 40 within a rectangular base frame 12 from which there also rises an outer frame or mask 13, concealing the inner frame 11. The mask 13 comprises opposite side walls 14 and a connecting front wall 15 having spaced shoulders 16 rising 45 and curving rearwardly therefrom and blending into the side walls 14. Covering the interior of the machine between the shoulders 16 is a hingedly displaceable cover 17 which follows substantially the contour of the shoulders 16 and 50 spreads laterally in a horizontal plane over two widely spaced ribbon spools indicated by dotted lines 21. The portion of the cover 17 between the said shoulders 16 is substantially coextensive with a nest of type-bar heads 22. The cover has 55 a finger piece 18 and is hinged upon pivot studs

23 projecting inwardly from the mask side-walls 14. When the cover 17 is displaced upwardly and rearwardly to the position indicated by the dotted lines in Figure 4, the interior of the machine is conveniently accessible for such purposes as cleaning the type heads and threading a typewriter ribbon into the machine.

Referring now for the moment more particularly to Figure 4, a platen carriage 24 is guided for letter-feed and return movements in the conventional manner upon a trackway structure 25 which forms part of the inner frame 11. The carriage has opposite end pieces 26 wherein a platen 27 is revolvably supported. The aforementioned cover 17, as may be seen in Figure 4, extends closely to the platen. The carriage is fed in letter-feed steps by a letter-feed spring, not shown, under the control of a conventional escapement, in a manner well known.

An electric motor 28 disposed at the left rear portion of the machine, see Figure 1, provides the motive power for returning the carriage and operating the typing instrumentalities. Since the carriage-return mechanism shown agrees with the one of the said patent to Helmond, it will be necessary only to describe it briefly. Extending rightwardly from the motor is a shaft 31 provided with pinion teeth 32 meshing with a gear 33, the latter being fixed on a spindle 34. A frame-supported housing 35 provides journals for the right end of the shaft 31 as well as for the spindle 34. A flanged drum 36 is normally rotatably loose on the spindle 34, and a draw band 37 is so attached to the said pulley as to be wound thereupon when the pulley is rotated counterclockwise of Figure 1. During use of the machine, the motor 28 rotates the gear 33 and spindle 34 continuously, but not the drum 36. Said gear has clutch teeth 38, and the pulley 36 has splined thereto a toothed clutch collar 41 which is rotatably loose on the spindle 34, but axially movable therealong from an open-clutch position to a position in which it is clutched to the said gear 33. A rock shaft 42, journaled in the casing 35, has fixed thereto a yoke 43 disposed in a groove in the clutch collar 41. An operating arm 44, fixed to the shaft 42, serves to rock said shaft and its yoke to move the clutch collar 41 to close and open the clutch. The draw band 37 passes over guide pulleys 45 and 46, onto a pulley 47 journaled on the left carriage end 26 and has an end so attached to and wound around the pulley 47 that rightward pull on the draw band will rotate the pulley clockwise. Fixed to and rotatable with said pulley is a bevel pinion 48 in constant mesh with a bevel gear sector 51 relatively mounted on the left carriage end 26. Said sector 51 is integral with a cam 52 for actuating a spring returned line-space lever 53 carrying a line-space pawl 54, the latter, when actuated, feeding a toothed line-spacing wheel 52 being unitarily revolvably with the platen 27. The actuation of the line-space lever 53 occurs upon the rightward pull of the draw band 37 resulting from an engagement of the clutch member 41 with the clutch teeth 38. Following the conclusion of the power carriage return, in a manner to be hereinafter described, a spring 56 returns the sector 51 to a normal position and thereby winds the band 37 upon the pulley 47. The pulley 36 on the spindle 34 is acted upon by a light spring 57 within a casing 58, in a manner to take up the slack in the band 37, without, however, overcoming the restoring spring 56 of the said sector 51.

A link 62 provides an operative connection be-

tween said arm 44 and arm 63 of a lever 64, the latter being pivoted at 65 to the machine framework and being normally restrained against clutch closing movement by a latch hook 66 of a pivoted lever 67. It will thus be seen that with said lever arm 63 normally latched, a spring 61 acting upon the arm 44 is normally restrained from closing the carriage-return clutch 38, 41. When it is desired to power-return the carriage, the operator effects an operation of a pivoted, spring-restored carriage-return lever 68, by depression of its key 71. This results in an actuation of the latch lever 67 which releases the lever 64 to the clutch closing action of the spring 61. The motor-driven rotation of the pulley 36 resulting from the closure of the clutch 38, 41, drives the carriage-carried pulley 47 and results first in the actuation of the line-spacing mechanism 53, 54. After a limited actuation of the line-spacing mechanism and consequently a limited rotative movement of the pulley 47, the band 37 picks up the carriage to effect its return.

The lever 64 is automatically restored to the control of the latch hook, at a predetermined point in the return of the carriage, responsive to the engagement of a margin stop 72 with a counterstop 73, the resulting effect being the disconnection of the clutch collar 41 from the clutch teeth 38 on the gear 33. The details, by means of which the lever 64 may be restored, are shown in the said patent to Helmond and their description and illustration are not deemed necessary for an understanding of the invention.

The latch lever 67, normally retaining the lever 64 against clutch-closing operation, has pivotally mounted thereon, and yieldingly operable thereby, a secondary latch 74, the latter being adapted to hold the arm 63 slightly lower than the latch hook 66 is capable of doing. Normally, however, this secondary latch is held out of cooperative range with the arm 63 by the upper end of the latch hook 66. Upon depression of the carriage-return key, the latch hook 66 is displaced rearwardly, permitting upward movement of the arm 63 behind the upper end of the secondary latch, the latter then resiliently pressing against the arm 63. At the completion of the carriage-return operation, the lever 64 is restored sufficiently far so that the secondary latch 74 will move over the arm 63, providing the carriage-return key is still depressed. In any event, the latch hook 66 will be in control of the lever 64 after the release of the carriage-return key.

Referring now again more particularly to Figure 4, type bars 76 are pivotally mounted in a semi-circular array, the aforementioned heads 22 of the bars being nested on a curved rest 77. The type bars may be power-actuated in the manner shown and described in the patent to Yaeger No. 2,254,764, dated September 2, 1941. Describing the power mechanism of this patent briefly, each type bar 76 has a link connection 78 with an upright sub-lever 81 which has a pendant arm 82 in rolling contact therewith. Connected to each arm 82 is an actuator 83 having its rear end urged upwardly and rearwardly against a bar 84 by a spring 85. The rear ends of the actuators 83 are adapted to be selectively drawn down to engage the snatch teeth with a toothed power shaft 87, under the control of type keys 88, the latter being on the front ends of spring-restored key levers 91 carrying hook-shaped members 92 whereby to draw the actuators downwardly. During use of the machine, the said power shaft 87 is driven by the spindle 34 through

a belt drive 93, and any actuator drawn into engagement with said toothed power shaft 87 will be operated by the latter, wherefore the type bar corresponding to the operated actuator will type.

In the circuit of the electric motor 28 is a tumbler or snap switch 94 of standard manufacture, secured to a bracket or ear 95 of the machine frame 11. The tumbler switch has an operating arm 96 which is operable from the front of the machine by a control knob 97 through connections presently to be described. The knob 97 is fast upon a stub-shaft 98 protruding from and pivoted in one of the shoulders 16 of the mask. Behind the shoulder 16 the stub-shaft 98 carries a disc 101, into a slot 99 of which a crank end 102 of a fore-and-aft extending shaft 103 extends. The crank shaft 103 is pivoted near its rear end in the said ear 95, whereas near its front end it is pivoted in another ear 104 of the mechanism-supporting frame 11. The rear end of the crank shaft carries fixedly a plate 105 provided with a stud 106 into a socket of which the switch arm 96 extends. Turning the knob 97 from the position of Figure 1 to the position of Figure 3 closes the tumbler switch 94. It may be noted at this point that the connection of the crank 102 with the disc 101 is such that the mask 13 may be removed readily from the inner frame 111. The plate 105 has articulated to an ear 107 thereon a rightwardly extending rod 108 which near its right end is slidably guided in a perforation 109 provided on a fixture 110. A right-angularly bent-off right end 111 of the rod overlies the arm 63 of the clutch-controlling lever 64 and is guided in a laterally disposed slot 112 of a bracket 113, the latter being rigidly secured to the said fixture 110. With the switch mechanism in the turned-off position, as in Figure 1, the rod end 111 exerts such control over the lever 64 that the right extremity of the arm 63 is held lower than the latch shoulder of both the latches 66 and 74. Should the switch mechanism, therefore, be turned off when the carriage-return key 71 is depressed, no carriage return will ensue unless the carriage-return key is reoperated after the switch mechanism has been turned on. In other words, no dangerous surprise movements by the carriage are possible due to an unauthorized or accidental operation of the carriage-return key 71 while the switch mechanism is turned off. It is here to be understood that under any condition, subsequent to the closure of the switch, the lever 64 will always be held by one of the latches 66 or 74 and that only a subsequent operation of the lever 67, as by the key 71, will be effective to cause closure of the clutch and consequently a power movement of the carriage. If, therefore, the switch should be opened while a carriage return movement is incomplete, the carriage will not be power-moved upon subsequent closure of the switch, except if followed by a new operation of the lever 67. It should here be observed that the left end of the slot wherein the rod end 111 is situated, see Figures 1 and 5, is parallel with the adjacent portion of the lever 64 and prevents the lever 64 from exerting any force on the rod 108 which would tend to close the tumbler switch 94.

In order to suppress or prevent opening of the cover 17, when the switch is turned on as illustrated in Figure 3, there is provided a lock lever 114 which, in the closed position of the cover, has an end 115 situated in a yoke 116. The lever 114 is pivoted upon the interior of the mask at 75

117 and has a leftwardly extending arm 118 which, in the turned-on position of the switch, is blocked against clockwise displacement by a dwell 121 on the disc 101. Consequently, when the switch is turned on as in Figure 3, it is impossible to open the cover. The disc 101 is so formed that in the open position of the switch the lever arm 118 has considerable capacity for movement toward the stub shaft 98 (see Figure 1); the disc 101 having a sharp drop-off or shoulder 122 adapted to cooperate with the lock arm 118 to prevent turning on of the switch when the arm is swung towards the stub shaft 98. The pivot axis of the cover is at a higher location than the yoke 116, and, consequently, the cover, in being displaced, swings initially in a forwardly inclined arc. During such initial displacement, the cover rocks the lock lever 114 in counterclockwise direction and thereby causes the arm 118 thereof to swing into switch-locking relation with the shoulder 122. After some displacement of the cover, the yoke 116 swings clear of the lever end 115; and from then on, pending the restoration of the cover, the lever 118 will remain in switch-locking position under the tension of a spring 124, wherefore power-typing and carriage-returning operations can only be effected when the cover is closed, and wherefore to call a power-return of the carriage into operation the cover must always be closed first.

With the carriage substantially centered, the cover 17 is displaceable to the position illustrated in dot-and-dash lines in Figure 4, that is, the wide portion of the cover is then located between the front portions of the opposite carriage ends 26, in a position obstructing carriage movement. However, no harm can come of this, since the carriage-return mechanism is then completely disabled.

In swinging the cover to normal position, the shorter prong 125 of the yoke passes in front of the lever end 115, whereas the longer prong 126 engages and actuates the latch lever 114. While the lever 114 is being actuated, the yoke 116 swings rearwardly and downwardly about the cover pivot pins 23 until the lever end 115 is fully between the said prongs, as seen in Figures 1 and 4, the knob 97 being then operable to close the motor circuit and enable carriage-return mechanism. The weight of the cover 17 is sufficient to overcome the tendency of the spring 124 to lift the cover. However, detents 127 may be provided to hold the cover more securely in closed position. The lever 114, to prevent its end 115 from flexing in a fore-and-aft direction, may have a firm guiding support near the said end, as indicated at 128.

While the invention has been described with reference to the details shown in the drawings, it is not restricted to the particular construction or method of operation set forth. The scope of the invention is as indicated in the following claims.

What is claimed is:

1. In a typewriting machine having a carriage, normally disabled power-driving means for said carriage, comprising, an electric motor and a normally open drive from said motor to said carriage, a switch to energize or deenergize said motor, control means operable to close said drive connection, wherefore, if said switch is closed, operation of said control means causes said carriage to be power driven, and means responsive to opening said switch to render said drive connection open if it has previously been closed.

2. In a typewriting machine having a carriage, normally disabled power-driving means for said carriage, comprising, an electric motor and a normally open drive from said motor to said carriage, a switch to energize or deenergize said motor, control means operable to close said drive connection, wherefore, if said switch is closed, operation of said control means causes said carriage to be power driven, and means responsive to opening said switch to render said drive connection open and/or to suppress closure of said drive connection by said control means.

3. In a typewriting machine having a carriage, normally disabled power-driving means for said carriage, comprising, an electric motor and a normally open clutch, a switch to energize and deenergize said motor, means movable to open and close said clutch, biased to close it, means adapted to hold said biased means after clutch opening movement, being operable to release said biased means for effecting closure of said clutch, and means so controlled by said switch that in response to motor deenergizing operation of said switch the said biased means is moved to open said clutch, said holding means including a provision whereby upon clutch-opening movement it will hold said biased means pending a new releasing operation.

4. In a typewriting machine having a carriage, power-driving means for said carriage, comprising, a normally open drive for said carriage, a cover displaceably mounted to uncover parts of the machine, and means to close and open said drive, including means so controlled by the position of said cover that said drive can only be in a closed state when said cover is substantially closed.

5. In a typewriting machine having a carriage, power-driving means for said carriage, comprising, a motor, and a normally open drive for said carriage, a cover displaceably mounted to uncover parts of the machine, means for closing and opening said drive, including means operable to render said drive open, and means so associating said cover with said rendering means as to compel the drive to be open whenever the cover is displaced.

6. In a typewriting machine having a carriage, power-driving means for said carriage, comprising, a normally open drive for said carriage, a cover displaceably mounted to uncover parts of the machine, and control means to open and close said drive, including means operable to one position to lock said cover, and operable to another position to unlock said cover and open said drive, said last means including a provision whereby it will be locked in said other position whenever the said cover is opened, whereby said cover can never be opened when said drive is closed, and whereby when said cover is opened the said drive cannot be closed.

7. In a typewriting machine having a cover displaceably mounted for uncovering parts of the machine, normally disabled power-driving means for said carriage, comprising, an electric motor and a normally open drive from the motor to the carriage, a switch to energize and deenergize said motor, means operable to close said drive, switch opening and closing means so controlled by the position of said cover that whenever said cover is open said switch must also be open, means to open said drive concomitantly with opening said switch, said last means being incapable of closing said drive, and means requiring said operable means to be operated in the closed position of

said switch in order to effect closure of said clutch.

8. In a typewriting machine having a carriage, normally disabled power-driving means for said carriage, comprising, an electric motor and a normally open drive from said motor to said carriage, a switch to energize or deenergize said motor, control means operable to close said drive connection, wherefore, if said switch is closed, operation of said control means will cause said carriage to be power driven, means responsive to opening said switch to render said drive connection open pending operation of said control means following closure of said switch, a cover displaceably mounted to uncover parts of the machine, and means adapted to render said cover undisplaceable while the motor is energized and adapted through displacement of said cover to lock said switch against motor energizing operation, wherefore, said drive connection cannot be closed by operation of said control means, except when the cover is closed.

9. In a typewriting machine having an electric motor for driving parts thereof, a cover displaceably mounted to uncover parts of the machine, a snap switch for said motor, including control means operable alternatively with a snapping action to a definitely defined open and to a definitely defined closed switch position, means operatively connected with said control means for concomitant operation therewith, and means governed by said cover in a manner to receive a positive movement therefrom during initial cover displacement and to return to original position during cover closure, said connected means and said governed means being devised for such cooperation, that the connected means in the said defined closed switch position blocks said governed means against reception of the said positive movement, and that upon receipt of said positive movement, said governed means blocks said connected means in the said defined closed switch position, wherefore the cover is only displaceable when the switch is open, and wherefore the switch can only be closed when the cover is closed.

10. In a typewriting machine having an electric motor for driving parts thereof, a cover hingedly displaceable in a wide arc on the machine, a switch for said motor, including control means operable alternatively to a definitely defined open and to a definitely defined closed switch position, means operatively connected with said control means for concomitant operation therewith, means supported independently of said cover and operable to block said connected means so as to block switch closing operation of said control means from said defined open switch position, said connected means being devised to obstruct operation of said independently supported means whenever said control means is moved to said closed switch position, and means to operate and restore said independently supported means respectively by displacement and restoration of said cover, comprising a normally established operating connection between a wide swinging part of said cover and said independently supported means, said connection being of a nature to become automatically severed after an initial cover displacement and to become automatically reestablished towards the end of the closing movement of the cover.

11. In a typewriting machine having a carriage normally disabled power-driving means for said carriage, comprising, an electric motor and

a normally open drive connection from said motor to said carriage, circuit opening and closing means, control means operable to close said drive connection, so that if said circuit is in a closed condition, operation of said control means will cause the carriage to be power driven, and means responsive to circuit opening by said circuit opening means, to render said drive connection open

5 if it has previously been closed, said responsive means including means devised to suppress upon response the closure of said drive connection by operation of said control means unless the circuit is first closed again and the control means operated subsequently to such circuit closure.

WILLIAM F. HELMOND.
